* cited by examiner

(73) Assignee: **Intec, Inc.**, Miami, FL (US)

Primary Examiner—Prabhakar Deshmukh

(**) Term: **14 Years**

(74) Attorney, Agent, or Firm—Liniak, Berenato & White

(21) Appl. No.: **29/193,773**

CLAIM

(22) Filed: **Nov. 14, 2003**

The ornamental design for a steering wheel assembly for a video gaming device, as shown and described.

(51) **LOC (7) Cl. 14-02**
(52) **U.S. Cl. D14/414; D14/416; D21/333;**

DESCRIPTION

D21/385; D21/566

(58) **Field of Search D14/400, 401,
D14/414, 416, 412, 432; D21/324, 333,
385, 477, 561, 566; 273/148 B; 463/1,
3, 30-47; 434/45, 46**

FIG. 1 is a perspective view of the steering wheel assembly for a video gaming device according to the present invention.

FIG. 2 is a left side view of the steering wheel assembly for a video gaming device of FIG. 1.

FIG. 3 is a left side view of the steering wheel assembly for a video gaming device of FIG. 2 in an alternate position.

FIG. 4 is a right side view of the steering wheel assembly for a video gaming device of FIG. 1.

FIG. 5 is a front view of the steering wheel assembly for a video gaming device of FIG. 1.

FIG. 6 is a rear view of the steering wheel assembly for a video gaming device of FIG. 1.

FIG. 7 is a top view of the steering wheel assembly for a video gaming device of FIG. 1; and,

FIG. 8 is a bottom view of the steering wheel assembly for a video gaming device of FIG. 1.
